(57) **CLAIM**

The ornamental design for an electrical cable connector, as shown and described.

DESCRIPTION

FIG. 1 is a top, right, front perspective view for an electrical cable connector in accordance with our design;

FIG. 2 is a bottom, left, front perspective view thereof;

FIG. 3 is a top, left, rear perspective view thereof;

FIG. 4 is a bottom, left, rear perspective view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a left side elevation view thereof; and,

FIG. 10 is a right side elevation view thereof.

The dashed broken line portions of the figures are included to show unclaimed subject matter only for the purpose of illustrating environment and form no part of the claimed design. The dash-dot broken lines define boundaries of the claimed design, and form no part of the claimed design.
